TAMPING APPARATUS

John Kalix, Dayton, Ohio

Application July 30, 1943, Serial No. 496,690

6 Claims. (Cl. 94—48)

(Granted under the act of March 3, 1883, as amended April 30, 1928; 370 O. G. 757)

The invention described herein may be manufactured and used by or for the Government for governmental purposes, without payment to me of any royalty thereon.

This invention relates generally to a soil compactor but more particularly to a soil tamping device adapted to be used for compacting earth surfaces to a desired depth preparatory to the construction of highways, dams, fills, levees and the like.

One object of the invention is to provide a device of the class described in which novel means are provided for tamping the soil so as to effectively provide a compact surface layer of uniform density.

Another object of the invention is to provide a means for rapidly and inexpensively constructing highways capable of bearing heavy traffic.

Still another object of the invention is to provide a device of the class described which is of simple, rugged, and inexpensive construction, which may be easily attached to a tractor.

Other objects and advantages reside in details of design and construction including novel means for effecting the tamping of the soil, an improved "sheep's foot" construction and means for the attachment of the rollers to the tractor.

These features will be more fully disclosed in the following description and in the drawings wherein like parts have been designated by similar reference characters and in which:

Fig. 1 is a side elevation showing the earth tamper coupled to a tractor;

Fig. 2 is a top plan view of the assembly shown in Fig. 1;

Fig. 3 is a partially sectionized view of a rearward portion of the coupling device;

Fig. 4 is an enlarged sectionized view taken on the line 4—4 of Fig. 2 showing the interior of the rollers and the water connections to the sheep's feet;

Fig. 5 is a partially sectionized view taken on the line 5—5 of Fig. 4 showing the axially mounted hammer and its operating mechanism;

Fig. 6 is a partially sectionized view of a portion of the hammer showing the roller lifting device in advanced position;

Fig. 7 is a partially sectionized view taken on the line 7—7 of Fig. 4 showing the water supply connections to the sheep's feet;

Fig. 8 is a view showing a section taken on the periphery of a roller as at 8—8 of Fig. 7, and illustrates the means of attachment of the sheep's feet;

Fig. 9 is a view showing a section taken on the

periphery of a roller as at 9—9, Fig. 8, and illustrates the water connection to the sheep's feet;

Fig. 10 is a partially sectionized view taken centrally and longitudinally through the center of a roller having a modified form of tamper mechanism;

Fig. 11 is a partially sectionized view taken on the line 11—11 of Fig. 10 showing an assembly of the modified form of tamper mechanism;

Fig. 12 is a partially sectionized elevation showing in detail the construction of the coupling device, the section being taken on the line 12—12 on Fig. 2;

Fig. 13 is a sectionized view of a modified form sheep's foot.

Briefly stated, the device comprises a roller adapted to be pulled by a tractor preferably equipped as a bulldozer by the attachment of a pusher blade to the forward end thereof. The roller which is coupled to the tractor by means of a tension link is provided with an internal tamping device which causes it to compress the earth as the rollers pass over it.

In the drawings, reference character 10 denotes a tractor provided with track rollers 11, 11', track 12, source of power 13, transmission pulleys 14 and 15, and transmission chain 16. The tractor is also provided with a driver's seat 17, and steering and control apparatus, designated respectively by the numerals 18 and 19, a pusher blade 20, and a water reservoir 21, the latter being connected to the sheep's feet 22 of rollers 23, as will be further described.

To the tractor is coupled the tamper 24 which comprises a group of ground rollers of like construction, each of which is designated by the numeral 23. These rollers encircle a shaft 26 which is mounted in a coupling yoke 28. The end rollers of the group are provided with spiders 110 which are axially connected to the shaft 26 and adapted to function as supports therefor as illustrated in Figs. 1, 2 and 4.

The coupling yoke 28 is formed with a central channel member 29 which serves as a spacer for upper and lower C shaped parallel yoke members formed of channel bars 30 and 30', between which and adjacent each end thereof are located rectangular spacer members 31, 32.

These rectangular members 31, 32 function as spacers to which the channels 30 and 30' are attached and also function as abutments for spring support members 33 and 34. The spring support members are of tubular shape, the central opening therein providing for the passage of drag shafts 25 therethrough, as shown in Figs. 2 and 3.

These tubular spring retaining members 33 and 34 are provided respectively with a flange 35, 36. The tubular portion of the spring support members 33 and 34 fit within springs 37 and the flanges 35, 36 abut the ends of the springs and the rectangular members 31 and 32.

To one end of each of the drag shafts 25 are attached the nuts 39 and to the other ends bracket members 27 which are formed with a tubular portion 41 for the reception of the roller shaft 26, and a downwardly extending flanged portion 42. The drag shafts 25 are provided with threaded ends on which are screwed the nuts 39 as mentioned above, to confine the springs 37 between the flanges of the tubular spring retaining members 33, 34.

As the tractor pulls the rollers, the springs 37 are compressed to thus furnish a resilient connection between the tractor and the rollers.

In order to brace the bracket members 27, they are riveted or otherwise suitably attached to gusset plates 46 which are provided with slots 6, and retained in slidable contact with the channel bars 30 by means of nuts 6'. With the forward movement of the tractor the yoke may move forward without movement of the coupling shafts 25 and brackets 27 until the springs 37 compress sufficiently to overcome the load of the rollers.

In order to provide an angular adjustment for the hammer so that the direction of its blows on the roller may be controlled by the operator, the coupling yoke is provided with a centrally mounted vertically arranged worm 47 having an elongated shaft 48 provided with a hand-wheel 49 at its upper extremity. The worm engages a swivelly mounted coupling member 50 carried by brackets 51 projecting from the rear of the tractor 10. By turning the hand-wheel the angularity of the hammer with respect to the surface of the ground may be either increased or decreased, since the non-rotatable shaft 26 is connected through bracket members 27' to the hammer.

On the under surface of the lower channels 30' of the coupling yoke 28 are mounted brackets 52 which pivotally support links 53, said links being pivotally connected to confiner members 54. Confiner members 54 are attached to the links 53 and are adapted to be pulled over the surface of the earth and to cut into the soil to outline the tamped area. The confiner members 54 have spaced openings 54' which register with an opening in the link 53 to receive bolt 55 for angularly adjusting said members about pivot 53'.

The hammer 38 comprises a solid disc-shaped member, the lower portion of which is substantially semi-circular in contour and the upper portion of which is formed with a central narrow section terminating in an arc of the same diameter as the semi-circular portion, and sloping surfaces extending from the arc at the top of the narrow section which terminate at the ends of the semi-circular perimeter. The hammer is provided with a central slotted opening 57 through which the shaft 26 passes and which permits of a reciprocating movement of the hammer as the drum rotates around it.

The reciprocating movement of the hammer with the rotation of the drum is effected by the combined action of a lower hammer roller 58 and upper projecting contact member 59 which engages the teeth 60 of a ratchet wheel 61 which is rotated with the drum 23 by means of the drag link 8. The semi-circular circumference of the hammer 38 is provided with a central sloping cam section 62 between which and the interior cir-

5 cumference of the drum or roller 23 the hammer roller 58 is located. The hammer roller 58 is rotatably mounted in a fork 63, the fork being provided with a central member or shaft 64 which extends within a hollow opening 65 in the hammer. The central fork member or shaft 64 is encircled by a helical spring 66 which is attached to the extremity of said central member 64 by a nut 67. The spring abuts the nut 67 and the interior walls of the hollow opening 65 adjacent its narrow entrance 68.

As the roller 23, which encircles the hammer, is pulled over the earth by the tractor, the hammer 38 is retained in its original upright position with respect to the ground by means of the bracket member 27' which engages the laterally extending hammer pin 44, and with the turning of the ground roller 23 the hammer rolls upon the lower hammer roller 58 and the upper hammer rollers 1 and 1', the latter rollers functioning to guide the ground roller 23 with the movement of shaft 26. By the action of the hammer roller 58 on the cam surface 62, the hammer 38 is elevated sufficiently so that, when the ratchet teeth 60 of the wheel 61 engage the contact elevator member 59, it is raised sufficiently to allow the disengagement of the hammer roller which is returned to its initial position by means of the spring 66, and when the hammer has been elevated a sufficient distance the ratchet releases the hammer, whereby it drops upon the hammer roller and thus presses the ground roller against the earth. Thus the reciprocating movement of the hammer is effected in the following manner, first by its partial elevation by means of the wedging action of the hammer roller, and then the hammer is further elevated by the camming action of the ratchet wheel 61 which, after raising the hammer to its maximum height, allows it to drop back onto the roller 58 again for a renewal of the cycle.

A modified form of roller is shown in Figs. 10 and 11. With this type of roller, tamping of the earth is effected by the centrifugal action of rotating members within the roller.

45 In this modified construction, the roller 70 is not rotatably mounted on a shaft but is provided with laterally projecting trunnions 71, 71', which are rotatably mounted in bearings 12, 12' which are attached to the drag shafts 25 of the coupling yoke 28. (See Figs. 1 and 10.)

55 The trunnions are provided with flanges which are attached to the circular side walls 8, 8' of the roller or drum, the latter being attached to the circularly formed angles 73, 73' which are fastened to the internal periphery of the roller. The trunnions 71, 71' are each formed with an annular portion 74, 74', which projects from the flanges towards the center of the roller. On these annular projections 74, 74' are mounted external and internal bearings 75, 75' and 76, 76'. The internal bearings support the axle or shaft 77 of a centrally located disc 78 which rotates within the drum or earth roller, and which is weighted circumferentially by drilling the rim alternately on either side thereof within a quadrant of approximately 90° as indicated by the numeral 79, and filling the drilled holes with lead or babbitt.

70 The external bearings 75, 75' form the mounting for a pendulum 80 which is formed with lateral walls 81, 81' which have the contour of a sector of approximately 90°. These side walls are united by an arcuate base 82 from which projects inner walls 83 and 84, similar in contour to the outer walls and extending in either side

of the disc 78 to divide the pendulum into a weighted portion 85 and a gear frame portion 86. In the weighted section the metal from which the pendulum is formed extends from the outer wall 81 to the inner wall 83 as illustrated in Fig. 10. Projecting from the outer wall 81' is a trunnion on which is mounted a pinion 88. This pinion 88 meshes with an internal gear 89 attached to the interior wall of the drum or roller 70. Within the outer wall 81' and inner wall 84 are mounted bearings 90, 90' which support a shaft 91 on which are keyed the pinion 92 and gear 93. The pinion 92 meshes with the pinion 88, and the gear 93 meshes with a pinion 94 which is keyed on shaft 95. On this shaft is also keyed a gear 96. The shaft 95 is held in bearings (not shown) which are mounted in the walls 81' and 84. The gear 96 meshes with a pinion 97 which is keyed to the disc shaft 11. Thus power is transmitted from the rolling drum 70 to the disc 78 through the train of gears comprising the internal gear 89, pinion 88, pinion 92, gear 93, pinion 94, gear 96, and pinion 97 to the disc 78.

The rotation of the disc 78 which is weighted in a portion of its periphery causes a vibratory movement of the drum which effects a tamping of the earth as the roller passes over it. The pendulum has only a swinging motion with the starting and stopping of the roller, and functions as a safety device to prevent the stripping of gears in cases of a sudden stop or start of the roller. In such instances, the pendulum may be swung out of its approximate vertical position or rotated without damaging the gears.

The rollers of either the hammer type or the vibratory type of tamping device are provided with sheep's feet through which water may be supplied to the earth as the roller passes over it. The water is supplied from the reservoir 21 mounted on the tractor and is fed to shaft 26 through a tube 98. In the case of the hammer type of roller, tube 98 is connected to shaft 26 through a suitable water connection 99. For the vibratory type of roller, tube 98 is attached to shaft 26 through a water connection of the rotary type.

In the hammer type of roller the water connection 99 is screwed into the end of the roller shaft 26 and connects with a central passage 100 through the shaft through which the water passes to a rotatable sleeve connection 101 from which it is piped through tubes 102 to the sheep's feet 22 on the periphery of the roller 23. In the vibrator type of the roller the rotatable water connection 99 is attached to a trunnion 71 and connects to a central tubular passage 103 therein. This passage turns in a radial direction and is connected by a tubular feed line 103' to the tubes 104 and 104' which encircle the inner periphery of the drum and which connect to the sheep's feet 22, as shown in Fig. 10.

The sheep's feet are formed with release valves as shown in Figs. 8, 9 and 13. In the type shown in Figs. 8 and 9 the valve is formed with a spring pressed piston 105 which projects slightly beyond the extremity of the foot and which has an enlarged beveled portion 105' adapted to seat on a ledge 106 within the tubular valve passage 107 of the foot. On passing over the ground the pressure exerted on the piston opens the valves against the action of the spring 108 and allows water to pass through the tubular passage 107. As the pressure is removed from the piston 105 the valve is closed by the spring and the passage

of water cut off. With this construction water is only allowed to pass through the valves when they are in contact with the earth.

A modified form of valve is shown in Fig. 13. In this type of valve the spring 108' is exterior to the tubular passage through the foot and the valve piston does not contact the earth but is operated by a pivotally mounted compression member 109, which is arcuate in form and which also functions to enclose the piston so that particles of soil will not enter the valve passage and prevent the operation of the valve.

Having thus described my invention, what I claim as new and wish to secure by Letters

15 Patent is:

1. A mobile tamping device adapted to be coupled to a tractor having a water supply reservoir, said device comprising a coupling yoke, a non-rotatable shaft supported by said yoke, tubular ground rollers encircling said shaft, pressure controlled water distributing sheep's feet mounted on said ground rollers, conduits connecting said sheep's feet to said reservoir, ratchet wheels rotatably mounted on said shaft within said ground rollers, links connecting said ratchet wheels to said ground rollers to effect simultaneous rotation therewith, a hammer roller mounted within each of said ground rollers, hammers provided with lower cam surfaces and laterally extending ratchet contact members mounted for reciprocatory movement upon said shaft within said ground rollers and adapted to respectively engage said hammer rollers and said ratchets to effect the elevation and release of said hammers to produce reciprocatory movement thereof with the rotation of said ground rollers.

2. A mobile tamping device adapted to be coupled to a tractor provided with a water supply reservoir, said device comprising a coupling yoke, a non-rotatable tubular shaft supported by said yoke, ground rollers encircling said shaft, water distributing sheep's feet projecting from said ground rollers, conduits through said shaft connecting said sheep's feet to said reservoir, pressure operated release valves connected with said sheep's feet, ratchet wheels rotatably mounted on said shaft within said ground rollers, a hammer roller mounted within each of said ground rollers, links connecting said ratchet wheels to said ground rollers to effect simultaneous rotation therewith, hammers provided with lower cam surfaces and laterally extending ratchet contact members mounted for reciprocatory movement upon said shaft within said ground rollers and adapted to respectively engage said hammer rollers and said ratchets to effect the elevation and release of said hammers to produce reciprocatory movement thereof with the rotation of said ground rollers.

3. A mobile tamping device adapted to be coupled to a tractor, said device comprising a coupling yoke, a ground roller rotatably mounted in said yoke, a weighted disc and a pendulum concentrically mounted for rotation and oscillation within said roller, and transmission means associated with the pendulum, the roller, and the disc, to effect the transmission of rotation of said roller to said weighted disc and thereby produce vibration thereof with a consequent tamping effect of the roller.

4. A mobile tamping device adapted to be coupled to a tractor, said device comprising a coupling yoke, a tubular-shaped ground roller rotatably mounted in said yoke, a weighted disc having a central shaft, and a pendulum concentrical-

ly mounted respectively for rotation and oscillation within said roller, a pinion keyed to said central shaft, an internal gear attached to the inner wall of said roller, and a gear train rotatably mounted within said pendulum and meshing with said internal gear and said central shaft pinion to transmit rotation of said roller to said weighted disc to thereby effect the vibration of said roller.

5. A mobile tamping device adapted to be coupled to a tractor provided with a water supply reservoir, said device comprising a coupling yoke, a tubular ground roller rotatably mounted in said yoke, water distributing sheep's feet projecting from said ground roller and through conduits to said reservoir, a weighted disc having a central shaft, and a pendulum concentrically mounted respectively for rotation and oscillation within said roller, a pinion keyed to said central shaft, an internal gear attached to the inner wall of said roller and a gear train rotatably mounted within said pendulum and meshing with said in-

10 ternal gear and said central shaft pinion to transmit rotation of said roller to said weighted disc to thereby effect the vibration of said roller.

6. A mobile tamping device adapted to be coupled to a tractor, said device comprising a coupling yoke, a non-rotatable shaft supported by said yoke, tubular ground rollers encircling said shaft, ratchet wheels rotatably mounted on said shaft within said ground rollers, links connecting said ratchet wheels to said ground rollers to effect simultaneous rotation therewith, hammers provided with a lower cam surface and a laterally extending ratchet contact member mounted for reciprocatory movement within said ground rollers, upper and lower hammer rollers mounted on said hammers, said lower hammer rollers and said ratchet contact members adapted respectively to engage said cam surfaces and said ratchets to effect the elevation and release of said hammers to produce reciprocatory movement thereof within said ground rollers.

JOHN KALIX.
